US00D760272S

(12) **United States Design Patent**
Li

(10) **Patent No.:** **US D760,272 S**
(45) **Date of Patent:** **** Jun. 28, 2016**

(54) **PORTION OF A DISPLAY SCREEN WITH GRAPHICAL USER INTERFACE**

(71) Applicant: **Tencent Technology (Shenzhen) Company Limited**, Shenzhen, Guangdong (CN)

(72) Inventor: **Rule Li**, Guangdong (CN)

(73) Assignee: **Tencent Technology (Shenzhen) Company Limited** (CN)

(**) Term: **14 Years**

(21) Appl. No.: **29/489,512**

(22) Filed: **Apr. 30, 2014**

(51) **LOC (10) Cl.** **14-04**

(52) **U.S. Cl.**

USPC **D14/487**

(58) **Field of Classification Search**

USPC D14/485-487

CPC G06F 3/0484; G06F 3/04842

See application file for complete search history.

(57) **CLAIM**

The ornamental design for a portion of a display screen with graphical user interface, as shown and described.

DESCRIPTION

FIG. 1 is a front view of a first embodiment of a portion of a display screen with graphical user interface showing my new design; and,

FIG. 2 is a front view of a second embodiment of a portion of a display screen with graphical user interface showing my new design.

The broken line showing of a portion of a display screen and a mobile device in FIGS. 1 through 2 forms no part of the claimed design. The broken line showing of text and portions of the graphical user interface in FIGS. 1 through 2 represents environmental subject matter and forms no part of the claimed design.

1 Claim, 2 Drawing Sheets
